UNITED STATES PATENT OFFICE.

HARRY H. STYLL, OF SOUTHBRIDGE, MASSACHUSETTS.

OPHTHALMIC MOUNTING.

1,103,449.

Specification of Letters Patent. Patented July 14, 1914.

Application filed April 22, 1914. Serial No. 833,765.

To all whom it may concern:

Be it known that I, HARRY H. STYLL, a citizen of the United States, residing at Southbridge, in the county of Worcester 5 and State of Massachusetts, have invented certain new and useful Improvements in Ophthalmic Mountings, of which the following is a specification.

My invention relates to improvements in 10 ophthalmic mountings and has particular reference to improved means for retaining a rigid bridge mounting in position on the face.

The leading object of my invention is the 15 provision, in connection with a rigid bridge mounting, of an improved automatically operating yielding guard which may be adjusted to properly bear upon the nose and position the mounting thereon, and which 20 will in addition satisfactorily grip the upper portion of the nose to resist any tilting tendency thereof.

A further object of my invention is the 25 provision in combination with a rigid bridge and adjustable means associated therewith, of a novel and improved guard which shall serve as a positioning or weight supporting as well as a gripping member.

Other objects and advantages of my im- 30 proved construction should be readily ap- 35 parent by reference to the following de- 40 scription taken in connection with the accompanying drawings, and it will be 45 understood that I may make any modifi- 50 cations in the specific details of construction 55 shown and described within the scope of the appended claims without departing from or 60 exceeding the spirit of my invention.

Figure I represents a fragmentary per- 40 spective view of one form of my invention. Fig. II represents a plan view of a slightly 45 modified form. Fig. III represents a view of a slightly modified construction of guard member. Fig. IV represents a fragmentary 50 view illustrating another construction of guard and bridge for use in conjunction therewith. Fig. V represents a slightly modified 55 form of guard employed in conjunction with a saddle bridge. Fig. VI represents a frag- 60 mentary view illustrating a slightly differ- 65 ent method of attaching the guard.

In the drawings, in which similar characters of reference denote corresponding parts, the numeral 1 designates an arched bridge having secured at each end a 55 lens clip 2, while secured to and extending rearwardly from the lens clip in that form shown in Fig. I is the guard arm 3 terminating in a head 4. Pivotedly secured to said head 4, as by the rivet 5, is the ear 6 on the 60 outer face and disposed near the lower end of the guard member 7, a spring 8 carried by the rivet having one end engaging the arm and the opposite end bearing against the guard to swing the upper end inward 65 into gripping position.

In that form of my invention shown in Fig. II, I have illustrated the arm as in Fig. I extending across the bridge, having the handle 9 on the front portion thereof, the 70 arm being intermediately twisted, however, to receive the securing screw 10 for retaining the device in position on the bridge. In this form I have shown the guard as actuated by a flat in place of a round spring, one 75 end of the spring being anchored by a slot in the rivet while the opposite end bears against the guard.

In Fig. III, I have illustrated a guard arm quite similar to that shown in Fig. I, 80 the guard in this instance being shown as actuated by a coil spring, but being provided at the upper end with a supplemental gripping member 11 attached preferably as by a loose rivet construction to allow this 85 gripping member to automatically adjust itself to the shape of the nose and secure a firm engagement therewith.

In Fig. IV, I have shown the guard sup- 90 porting arm as forming a direct continua- 95 tion of the bridge, while the guard is pro- 100 vided with a supplemental gripping member 11 connected thereto by means of a loop 12, facilitating adjustment of the pad as de- sired.

In Fig. V, I have shown a further modi- 100 fication of my guard in which the sup- 105 plemental gripping member 11 is secured to the main guard at its rear edge and is swung inwardly as by the spring 13 to secure a firmer engagement between the front edge of the supplemental gripping member and the

nose to prevent any possibility of forward tilting of the mounting.

While the arm 3 may be formed from any desired character of material, I preferably construct it of material sufficiently pliable to permit of adjustment of the position of the guard 7 to correctly fit the nose and at the same time sufficiently rigid to retain the guard in its position. Under ordinary serv- 10 ice conditions in use the said arms are so adjusted as to cause the lower part of the guard adjacent the lug 6 to correctly bear again the nose and support the mounting in correct position thereon, while the upper 15 portion of the guard swung inward under the action of the spring 8 fits into the socket at the top of the nose and engages the loose flesh at this point to anchor the mounting in position, this action being more especially 20 noticeable when the supplemental upper gripping members are employed, as illustrated in certain of the figures of my invention, although it will be understood that their use is not required for the operation 25 of the mounting, although saving a certain amount of adjustment of the main guard and also proving of additional efficiency in connection with some noses.

The mounting having been correctly fitted, as mentioned above, in placing the same in position it is merely necessary to slide the same inward and upward onto the nose with a rolling movement, when the nose will automatically wedge or swing open the guards 35 7 against the tension of the springs 8. This movement is continued until the mounting reaches the correct position on the nose, that is, until the upper ends of the guards fit into the sockets at the top of the nose and grip- 40 pingly engage the loose flesh thereof.

It is to be noted that the shoulders of the heads 4 serve as stops to limit the pivotal movement of the guards, thus insuring their upper portion being sufficiently spaced to 45 readily receive the nose therebetween. Attention is also called to the fact that the guards, as is clearly shown in Fig. II, are dispersed at an angle to each other, this angle being preferably slightly greater than that of the nose so that the bearing portions rather than the rear edges of the guards will contact with the nose as the mounting is placed in position, while the front edges will engage the nose when the mounting is 50 55 in position and will prevent forward slipping of the mounting.

To further facilitate the comfortable positioning of the mounting I may, if desired, round or curve the upper ends of the guards 60 as indicated in Figs. I, II and IV for example, these rounded ends being first placed in engagement with the nose to initially open the guards and the mounting being then pressed into place with the rolling

movement previously described. In any 65 event, with my improved construction the mounting is securely and comfortably retained in place and held against accidental dislodgment although readily removable by a reversal of the positioning operation, that is by imparting an outward and downward 70 rolling movement thereto.

I claim:

1. A mounting of the character described, embodying a rigid bridge, adjustable supports carried thereby, guards fulcrumed adjacent the lower portions thereof, and yielding means for swinging the upper ends of said guards inward into gripping engagement with the nose. 80

2. In an ophthalmic mounting, the combination with the lenses, of a bridge rigidly connecting the same, rigid but adjustable arms extending rearwardly from the bridge and terminating in pivot heads, pivots carried by said heads, guards having pivot lugs disposed near the lower end thereof and mounted upon the pivots and a spring carried by each pivot having one end held against movement and the other end engaging the guard above the point of pivotance thereof for swinging the upper end of the guard inward into engagement with the nose. 85

3. In an ophthalmic mounting, the combination with the lenses, of a bridge rigidly connecting the same, rigid but adjustable looped arms extending rearwardly from the bridge, a guard pivotally secured adjacent the terminus of each of the arms, an actuating spring carried by the arm for swinging the upper end of the guard inward toward the nose and a supplemental adjustable gripping member carried by the upper end of the guard for grippingly engaging the 105 nose. 95

4. In an ophthalmic mounting, the combination with lenses, of a bridge rigidly securing the same in alinement, adjustable supports secured to the mounting, pivots adjacent the ends of the supports, guards pivoted on the pivots, springs on the pivots adapted to yieldingly operate the guards toward the nose and interacting stops between the supports and guards adapted to 110 limit the movement of the guards on the pivots. 115

5. In an ophthalmic mounting, lenses, a rigid bridge connecting the lenses, rearwardly extending supports, guards, fulcrum connections between the supports and the guards, springs adapted to operate the guards and adjustable bends in the supports intermediate the lenses and the guards. 120

6. In an ophthalmic mounting, the combination with the lenses, of a bridge rigidly connecting the same, rigid guard supports, and automatically operating guards carried 125

by the supports and disposed at a greater angle than that of the nose to be engaged thereby.

7. The combination with a bridge and stationary guard supports carried thereby, of guards pivoted to the supports, and means for swinging the upper ends of the guards inward, said guards having flaring upper

ends to facilitate positioning of the mounting.

In testimony whereof I affix my signature in presence of two witnesses.

HARRY H. STYLL.
